UNITED STATES PATENT OFFICE.

ALLEN HERMAN KERNGOOD, OF BALTIMORE, MARYLAND, ASSIGNOR TO ALMA MANUFACTURING COMPANY OF BALTIMORE, OF BALTIMORE, MARYLAND, A CORPORATION OF MARYLAND.

APPAREL-BUCKLE.

1,333,260.

Specification of Letters Patent.

Patented Mar. 9, 1920.

Application filed November 17, 1919. Serial No. 338,433.

To all whom it may concern:

Be it known that I, ALLEN HERMAN KERNGOOD, a citizen of the United States, residing at Baltimore, in the State of Maryland, have invented certain new and useful Improvements in Apparel-Buckles, of which the following is a full, clear, and exact description.

The object of the invention is to furnish a relatively flat buckle for use especially upon vests, trousers and other wearing apparel, which is, together with other advantages, devoid of unsightly and obtrusive projections when in use.

The invention consists of a buckle having a frame made of sheet metal, preferably steel, of such construction that the tongue-pivoting means will not extend beyond the face or back planes of the frame; the tongue preferably being of the so-called "cow-horns" variety, that is, of conventional staple or U-form, and pivotally mounted upon and secured to an intermediate cross-bar centrally depressed to afford a seat for the tongue, as I will proceed to explain and finally claim.

In the accompanying drawings, illustrating my invention, in the several figures of which like parts are similarly designated, Figure 1 is a top plan view also showing the lugs in dotted lines as they would appear before being closed over the tongue. Fig. 2 is a longitudinal section on line A B of Fig. 1. Fig. 3 is a bottom plan view. Fig. 4 is a side elevation. Fig. 5 is a section on line C D, and Fig. 6 is a section on line E F of Fig. 1. Fig. 7 also is a section on line E F of Fig. 1 showing the tongue raised and held against further backward movement.

The frame is composed of similar concavo-convex side-bars 1; concavo-convex end bars 3 and 4, which last has its inner portion extended inwardly substantially parallel with the level of the frame to form a lip 5 to receive the tips of the prongs of the tongue, and an intermediate substantially central cross-bar 6 springing from the inner portions of the end-bars 1 and having a substantially central depression 7 to receive the tongue and provided with the lugs 8 and 9, preferably of unequal length, extending respectively forwardly and rearwardly as indicated by the dotted lines in Fig. 1 and adapted to be bent over the tongue to form

a hinge-knuckle to pivotally secure the tongue to the cross-bar in the depressed seat 7 provided therein for it.

The cross-bar 6 has its ends 10 made concavo-convex to strengthen it and preserve the symmetry of the frame, and the central depression 7 is reversely curved to receive the head of the tongue, or it may be substantially flat. This central depression has the shoulders 11 connecting it with the ends 10 and these shoulders aid in fixedly locating the tongue and prevent its undue sidewise motion. The rearward edge of the depression 7 extends upwardly adjacent to the shoulders 11 to form stops 12 which limit the backward movement of the tongue, as indicated in Fig. 7, and so prevent the annoyance due to the tongue turning entirely over backwardly. The lugs 8 and 9 are adapted to be closed or folded over the head of the tongue to secure it pivotally to the cross-bar, their edges meeting in a butt-joint over the head of the tongue. These lugs are in one integral piece with the other members of the frame.

The tongue 13 may be of any approved form, preferably staple or U, and is here shown as of the so-called "cow-horns" variety or type, having the prongs 14 and the connecting head 15, shaped substantially as shown.

The head of the tongue is placed in the depression in the cross-bar with the prongs extending toward the lip 5, and the lugs 8 and 9 are closed over the head as shown in full lines Fig. 1 and in Fig. 5. The hinge portion of the tongue and the cross-bar itself thus lie wholly within the front and back planes of the frame, without projection beyond them in either direction, so that there is no unsightly or obstructive or obtrusive projection, and a flatness and symmetry of the buckle is obtained. The depression in the cross-bar beneath the lugs and the shoulders on both sides of them serve to hold the tongue in position, limiting it to the space especially provided for it and preventing it from riding in either direction along the cross-bar. The lugs are sufficiently strong to hold the tongue in position and being narrower than the length of the head allow the tongue to be readily moved without binding; and the tongue may be readily and freely moved to effect penetration of the strap and when closed the tips of its prongs

will lie upon the lip 5, but the tongue cannot fall backward toward the rear end bar because arrested by the stops 12.

Variations in the details of construction 5 are permissible within the principle of the invention and the scope of the claims following.

What I claim is:—

1. An apparel buckle, having a frame provided with a substantially central cross-bar having a central depression arranged wholly within the front and rear planes of the frame and constructed with front and rear lugs, and a tongue having its head located in said depression and engaged by the lugs.
2. An apparel buckle, having a frame provided with a substantially central cross-bar having a central depression arranged wholly within the front and rear planes of the frame and constructed with front and rear lugs, and laterally disposed shoulders, and a tongue having its head located in said depression and engaged by the lugs.
3. An apparel buckle, having a frame provided with concavo-convex side-bars and

end-bars and a cross-bar springing from the side-bars and having a central laterally shouldered depression and front and rear lugs on the edges of such depression, and a staple-shaped tongue having its head arranged in said depression between its shoulders and embraced by the lugs.

4. An apparel buckle, having a frame provided with concavo-convex side-bars and end-bars and a cross-bar springing from the side-bars and having a central laterally shouldered depression provided with stops at its rear adjacent to said shoulders, and front and rear lugs on the edges of such depression, and a staple-shaped tongue having its head arranged in said depression between its shoulders and embraced by the lugs.

In testimony whereof I have hereunto set my hand this 17th day of November, A. D., 1919.

ALLEN HERMAN KERNGOOD.

Witnesses:

PHILIP F. LARNER,
Wm. H. FINCKEL.

It is hereby certified that the assignee in Letters Patent No. 1,333,260, granted March 9, 1920, upon the application of Allen Herman Kerngood, of Baltimore, Maryland; for an improvement in "Apparel-Buckles," was erroneously described and specified as Alma Manufacturing Company of Baltimore, of Baltimore, Maryland, whereas said assignee should have been described and specified as *Alma Manufacturing Company of Baltimore City, of Baltimore, Maryland*, as shown by the record of assignments in this office; in the printed specification, page 1, line 85, for the word "conecting" read *connecting*; and that the said Letters Patent should be read with these corrections therein that the same may conform to the record of the case in the Patent Office.

Signed and sealed this 30th day of March, A. D., 1920.

[SEAL.]

M. H. COULSTON,
Acting Commissioner of Patents.
